UNITED STATES PATENT OFFICE.

EDWARD POOLE, OF PHILADELPHIA, PENNSYLVANIA, ASSIGNOR TO THE
IVINS, DIETZ & METZGER COMPANY, OF SAME PLACE.

DESIGN FOR CARPET.

SPECIFICATION forming part of Design No. 25,683, dated June 23, 1896.

Application filed May 22, 1896. Serial No. 592,688. Term of patent 3½ years.

To all whom it may concern:

Be it known that I, EDWARD POOLE, a subject of the Queen of Great Britain, residing at Philadelphia, county of Philadelphia, and State of Pennsylvania, have invented and produced a new and original Design for Carpet Fabrics, of which the following is a full, clear, and exact description, reference being had to the accompanying drawing, which forms a part of this specification.

My design, as shown in the drawing, consists in a new design for the body and border of a carpet fabric.

In the drawing, A represents the body, and B the border. The body A essentially is provided with a dark ground upon which are formed in lighter contrast the figures shown. The border A is formed, essentially, with light and

dark ground with separating lines of the form shown. Upon the ground of the border B are the figures as shown in the drawing.

Having now fully described my invention, what I claim, and desire to protect by Letters Patent, is—

1. In a design for a carpet fabric, the body A, substantially as shown.
2. In a design for a carpet fabric the border B substantially as shown.
3. The design for a carpet fabric comprising the body A and the border B.

In testimony of which invention I have hereunto set my hand.

EDWARD POOLE.
